UNITED STATES PATENT OFFICE

WILLIAM EYERNSCHMALZ, OF MILWAUKEE, WISCONSIN

NECKTIE

Application filed May 3, 1929, Serial No. 360,182, and in Germany May 3, 1928.

This invention relates to improvements in neckties. It is one of the objects of this invention to provide a necktie of the ready-tied variety, in which means is provided for easily and quickly securing said tie to the collar.

A further object of this invention is to provide an improved necktie having means therein co-operating with the collar button to hold said tie properly in position.

A further object of this invention is to provide an improved necktie which is simple in construction and neat in appearance, and inexpensive to manufacture.

With the above and other objects in view, the invention consists of the improved necktie and all its parts and combinations as set forth in the claims, and all equivalents thereof.

In the accompanying drawing, in which the same reference numerals designate the same parts in all of the views:

Fig. 1 is a front view of the tie, showing it in attachment with a collar, parts of the collar being broken away;

Fig. 2 is a similar view showing the necktie positioned adjacent the collar before it has been pushed up into final position, parts being broken away;

Fig. 3 is a sectional view taken on line 3-3 of Fig. 1;

Fig. 4 is a sectional view taken on line 4-4 of Fig. 3;

Fig. 5 is an enlarged sectional view taken on line 5-5 of Fig. 3; and

Fig. 6 is a sectional view similar to Fig. 3, showing a modification.

Referring more particularly to the drawing, the numeral 8 designates a necktie which has an upper portion 9 of knot formation. The said knot formation is formed by securing the upper portion of the tie around a forming member 10, which is originally hollow as at 11. The said member may be made of any rigid or semi-rigid material. A securing member 12 is positioned within the recess 11 of the knot forming portion 10, and is held in position by rubber which is poured in said recess 11 around said securing member 12.

The securing member is preferably made of rubber, but may be constructed of any yield-

ing material. Said securing member is formed with a slit 13 which widens inwardly to form a channel 14. At the upper end of the channel and slit is an enlarged opening 15 communicating therewith. The side walls of the channel are formed with a plurality of ridges 16. Positioned over said securing member is a covering portion 17, which is also formed with a slit 18 having an enlarged upper portion 19. The said slit is adapted to register with the slit in the securing member.

The collar 18' is of ordinary construction, and its ends are held together by a collar button 20, which is formed on its outer end with a ribbed head 21.

In adjusting the necktie in place, the head 21 of the collar button is inserted through the opening 19 of the covering member 17, and through the enlarged opening 15 of the securing member. The tie will then be in the position shown in Fig. 2. The knot portion of the tie is then gripped and pushed upwardly until it assumes the position shown in Figs. 1 and 3, where the collar button is held within the channel. By moving the knot one way or the other on the collar button, it is possible to vertically adjust the tie with respect to the collar to attain the exact position desired. As the ribbed sides of the channel yieldingly engage the ribbed head of the collar button, the tie will be held very securely in any adjusted position. To take off the tie, it is merely necessary to move the knot portion downwardly until the head of the button is within the enlarged portion 15, at which point the tie may be readily disengaged from said button by pulling outwardly.

It is to be noted that the improved necktie may be used with any type of collar. It is further to be noted that the ordinary type of collar button may be employed, although the type shown with the ribbed head is preferable, and forms one of the features of the invention.

In the modified form of device shown in Fig. 6, instead of employing a knot forming member 10 and a separate securing member 12, the knot is formed around a single piece of hard rubber or other yielding material, which is indicated by the numeral 10' in Fig.

6, the said member 10' having the slit 13 and ribbed channel formed therein.

Although only two forms of the device have been shown and described, it is obvious that various modifications may be made without departing from the spirit of the invention, and all such changes are contemplated as may fairly come within the scope of the claims.

What I claim is:

- 10 1. A necktie comprising a body portion having a recess in its inner side, said recess having ribbed yielding side walls, and a collar button having a ribbed head which is adapted to enter said recess, said recess permitting vertical adjustment of the necktie on said collar button, and said ribbed yielding side walls of the recess being adapted to grip the collar button to securely hold the necktie in any adjusted position.
- 20 2. A necktie comprising a section of material having a portion of knot formation, a securing member constructed of yielding material in connection with the inner side of said portion of knot formation, said securing member having a slit therein widening inwardly to form an inner channel and having an enlarged opening communicating with an end of said channel, and a collar button adapted to have its head enter said channel by way of the enlarged opening to hold the necktie in position.
- 30 3. A necktie comprising a section of material having a portion of knot formation, a securing member constructed of yielding material in connection with the inner side of said portion of knot formation, said securing member having a slit therein widening inwardly to form an inner channel and having an enlarged opening communicating with an end of said channel, the side walls of said channel being ribbed, and a collar button adapted to have its head enter said channel by way of the enlarged opening to hold the necktie in position.
- 40 45 4. A necktie comprising a section of material having a portion of knot formation, a securing member constructed of yielding material in connection with the inner side of said portion of knot formation, said securing member having a slit therein widening inwardly to form an inner channel and having an enlarged opening communicating with an end of said channel, the side walls of said channel being ribbed, and a collar button having a ribbed head which is adapted to enter said channel by way of the enlarged opening to hold the necktie in position.

In testimony whereof, I affix my signature.

WILLIAM EYERNSCHMALZ.
